UNITED STATES PATENT OFFICE.

DAVID L. KEELER, OF GRAND RAPIDS, MICHIGAN.

SEWING-MACHINE.

SPECIFICATION forming part of Letters Patent No. 334,442, dated January 19, 1886.

Application filed November 11, 1884. Serial No. 147,664. (Model.)

To all whom it may concern:

Be it known that I, DAVID L. KEELER, a citizen of the United States, residing at the city of Grand Rapids, in the county of Kent 5 and State of Michigan, have invented certain new and useful Improvements in Sewing-Machines, of which the following is a specification.

My invention relates to that part of a sewing-machine which feeds or moves the fabric to the needle; and the object of my invention is to regulate the length of the stitch by means of an adjustable incline or wedge, as herein-after fully described. I attain this object by 15 means of the mechanism illustrated in the accompanying drawings, in which—

Figure 1 is a perspective view of an incline washer used upon the eccentric-rod. Fig. 2 is a plan view of the under side of the bed-plate of a sewing-machine to which my invention is applied. Fig. 3 is a side view of the adjusting-bar C, showing its connection to the bed-plate. Fig. 4 is a perspective view of the bar C, and Fig. 5 a plan view of a modified 25 form of a portion of the feeding device shown in Fig. 2.

Similar letters refer to similar parts throughout the several views.

E is the bed-plate of a machine as seen from 30 the under side.

J is the shaft, to which is rigidly attached the eccentric H, which eccentric gives the longitudinal motion to the eccentric-rod G.

F is the feed-bar, bent at one end, as shown, 35 and provided with an opening, through which the bolt A passes, so as to allow the feed-bar to move freely upon the bolt. The bolt A is provided with a head, as shown in the drawings, and the lower end of A terminates in a 40 screw, which engages with a screw-thread cut in an opening in the eccentric-rod G.

Between the head of bolt A and incline or wedge O is the washer B, one side resting against the head of A and the other side 45 inclined, as shown, so as to fit against the wedge O.

Between the washer B and the feed-bar F is the wedge O, which is provided with the slot P, for the reception of the neck of bolt A. 50 The wedge O is or may be formed in one and the same piece with the regulating-bar C, as shown.

L is a washer between the plate E and the bar C. It has a tongue or slide rigidly attached, which fits into and slides in the slot D 55 in the plate.

N is a screw, which holds the washer in place and supports one end of the bar C. It passes through the hole M of the bar C, and also through the washer L, and extends beyond 60 a sufficient distance to allow the adjusting-nut K to be attached thereto.

Q is a set-screw for adjusting bolt A to any required position. The spring S operates merely to hold the feed-bar against the feed-bar 65 cam to keep it from rattling. The machine works equally well without it, except that without this spring the machine makes more noise in running.

Instead of using the beveled washer B, it 70 may be dispensed with, as shown in Fig. 5, in which case the washer may be dispensed with entirely, or a thin metallic or leather washer used instead; and instead of having the bolt A adjustable, as above described, it 75 may be rigid with the eccentric-rod G, as also shown in Fig. 5.

The eccentrics H and cam I are the same as those in ordinary use in sewing-machines.

The operation of my invention is as follows: 80 To shorten the stitch, the nut K is loosened and the bar C moved in the direction indicated by the arrow. This pushes back the incline O. The shaft J is then revolved, and the eccentric H brings the head of A near to 85 the feed-bar F before acting upon it, so that as the eccentric revolves the longitudinal movement of the feed-bar F will be very slight. By loosening nut K and moving the bar C in the direction opposite to the one above described 90 90 incline O is drawn between the head of A and feed-bar F, and by again setting the shaft J in motion the feed-bar F is moved longitudinally to the full extent of the eccentric, giving a very long stitch. It will be seen that by the 95 means above described the length of the stitch may be readily adjusted to any desired length between the maximum and minimum points, which adjustment can be made with great facility and accuracy.

Having thus described my invention, what I claim to have invented, and desire to secure by Letters Patent, is—

1. In a sewing-machine, the combination of

the feed-bar F with the eccentric-rod G, bolt A, and incline O, said incline being adjustable, so as to shorten or lengthen the stroke or movement of the feed-bar, thereby regulating 5 the length of the stitch, substantially as described.

2. The combination of the incline O, the incline-washer B, the bolt A, eccentric-rod G, and feed-bar F, said incline O being adjustable longitudinally between the end of feed-bar F and the head of bolt A, substantially as described.

3. The combination of the feed-bar F, eccentric-rod G, and bolt A, said bolt A being adjustable longitudinally in the eccentric-rod, 15 substantially as and for the purpose described.

4. The combination of the following parts, viz: shaft J, eccentric H, rod G, feed-bar F, adjustable bolt A, and incline O, substantially as and for the purpose described.

DAVID L. KEELER.
